UNITED STATES PATENT OFFICE.

ELMER E. POOLE, OF BOSTON, MASSACHUSETTS.

HOLDER FOR TAIL-LIGHTS AND NUMBER-PLATES FOR AUTOMOBILES.

1,236,816.

Specification of Letters Patent.

Patented Sept. 4, 1917.

Application filed July 14, 1915. Serial No. 39,907.

To all whom it may concern:

Be it known that I, ELMER E. POOLE, a citizen of the United States, residing at Boston, county of Suffolk, State of Massachusetts, have invented a certain new and useful Improvement in Holders for Tail-Lights and Number-Plates for Automobiles, of which the following is a specification, reference being had therein to the accompanying drawings.

The invention relates to a new and useful improvement in tail light and number plate holder for automobiles. One object of the invention is to provide a holder to which the number plate can be quickly and securely attached and from which the plate can be quickly removed when desired, yet the plate be secure from accidental detachment; another object is to provide a combination holder for the tail light and number plate so formed and constructed that the number is clearly illuminated by the same lamp that illuminates the bulb's eye for the tail light.

The invention will be fully understood from the following description when taken in connection with the accompanying drawings and the novel features thereof will be pointed out and clearly defined in the claim at the close of this specification.

In the drawings,—Figure 1 is a front elevation of a device embodying the invention with the lamp and number plate attached thereto.

Fig. 2 is a section on line 2—2 of Fig. 1 except that the spring is shown in side elevation.

Fig. 3 is a front elevation of the holder alone, the number plate being removed.

Fig. 4 is a section on line 4—4 of Fig. 3. Referring now to the drawings, the body 1 of the holder which is preferably of sheet metal is formed with a plurality of hooks or clips 2 which project outwardly in front and then downwardly so that the upper edge of a number plate 3 may be engaged under these clips. Preferably the clips are struck up out of the sheet metal which forms the body of the holder.

A ledge or flange 4 projects out in front of the lower part of said body 1 so that when the number plate 3 is engaged by the clips 2 the number plate which extends down below the ledge 4 will rest against the edge of the ledge and be maintained in a plane at an inclination to the body of the holder, that

is, causing the lower edge of the number plate to stand out, thereby giving a cant to the number plate so that the light from the lamp above will be thrown more directly upon the face of the number plate.

Extending down from the lower end of the body of the holder is a yoke or hanger 5 having two branches 6 each formed with a hook 7 which engages with the lower edge of the number plate.

The flange 4 at the lower end of the body of the holder is preferably formed by bending the sheet metal that forms the said body, making a fold as shown, thus giving greater strength, and preferably also a bar 8 is inserted between the two horizontal portions of the fold to serve as additional strengthening and stiffening means.

The yoke 5 is secured to the flange 4 by means of a screw 9 whose head is at the lower end, the screw passing up through a hole in the yoke and through a hole in the flange and the interposed bar 8. The hole through which the screw passes is threaded for engagement with the screw so that the screw will not fall out and the screw is of sufficient length so that by turning it up or down the yoke may be adjusted up and down. Before the number plate is put in position, the yoke should be lowered by turning the screw 9 down far enough so that the lower edge of the number plate can be seated in position on the hooks 7 and the upper edge be slipped under the clips 2 and then the screw 9 should be set up to clamp tightly the number plate between the hooks 7 and the clips 2.

It is not really necessary in order to insert the number plate that the yoke should be lowered far enough for the plate to clear the lower ends of the clips 2, because the number plate can be inserted endwise, but preferably the yoke is lowered far enough so that when the plate is seated on the hooks 7 the upper edge of the plate may be allowed to tip back against the body of the holder without striking the clips 2 and then setting up the screw 9, the yoke and the number plate will be drawn up to tightly clamp the number plate between the hooks 7 and the horizontal offset 10 of the clips 2.

As an additional means for supporting the lower edge of the number plate there is preferably provided a coil spring 10 the upper end of which is secured to the holder plate and the lower end of which is formed

with a hook 11 which is adapted to be engaged with the lower edge of the number plate. The upper end, which is secured to the holder plate, is shown as connected with 5 a bracket 12 which is fastened to the back side of the body of the holder plate. The spring 10 is normally contracted as shown in the drawings. When the number plate is about to be inserted the lower edge there- 10 of will be seated on the back portion of the spring while the plate is held in the hands, and then the plate is pressed downward, thereby expanding the spring and allowing the upper edge of the number plate to drop 15 back past the lower ends of the clips 2, then relaxing the downward pressure of the hands on the number plate and allowing the spring to contract, the spring will carry the number plate up until the upper edge is 20 pressed against the offsets 19 of the clips 2, and hold the plate securely while the screw 9 is being set up. If the spring 11 is made of sufficient tension and strength the yoke 5 and hooks 7 may be entirely dispensed with, but 25 it is preferable to use both the yoke and the spring.

The holder is provided with an extension top 13 in which is held a lamp holder 14 to hold a lamp 15. The extension top is 30 provided with a hood portion 16 having a downwardly extending front 17 in which is held a bull's eye 18 in front of the lamp 15. The hood is open at the bottom so that the light from the lamp is thrown down and

strikes the inclined front face of the number 35 plate.

The hood flares away from the lamp in a curve toward each end and its inner surface forms a reflector extending toward each end of the number plate, and preferably substantially the length of the number plate. 40

What I claim is:

A holder for a tail light and number plate having a body portion, a clip projecting from the body portion to engage over the 45 top edge of a number plate, a hanger secured to the lower part of the body of the holder having at its lower end hooks which are adapted to engage the lower edge of the number plate, means for adjusting said 50 hanger at different elevations and of drawing it up so that the hooks which engage the lower edge of the number plate will draw up the number plate and clamp it firmly against the said top engaging clips, the body portion having a projection from the face thereof which causes the number plate to stand in a plane inclined to a vertical plane, and the upper portion of the holder having a lamp holding portion which is adapted to 55 hold a lamp in position projecting out beyond the plane of the number plate. 60

In testimony whereof I affix my signature, in presence of two witnesses.

ELMER E. POOLE.
